UNITED STATES PATENT OFFICE

MAURICE DE WITT HIRST, OF OCEAN CITY, NEW JERSEY, ASSIGNOR OF ONE-HALF TO
LEROY A. GOODWIN, OF PHILADELPHIA, PENNSYLVANIA

DEGREASING APPARATUS

Application filed September 17, 1927. Serial No. 220,241.

This invention relates to degreasing systems of the type in which the liquid used for cleaning purposes may be clarified so that such liquid can be used repeatedly.

5 An object of the invention is to provide an apparatus of the type specified in which an anhydrous neutral liquid may be used as the solvent.

Another object is to provide an apparatus 10 in which the liquid may be used repeatedly without loss through evaporation, or other causes.

Another object is to provide means for distilling the dirty liquid used in a degreasing 15 apparatus.

Another object is to provide a degreasing apparatus which eliminates all danger of fire or explosion.

Another object is to provide an apparatus 20 of the type specified in which all odor is eliminated, thereby permitting pressing of the materials immediately upon their removal from the apparatus, when such materials are wearing apparel.

25 Another object is to provide a degreasing apparatus with means for removing all the adhering solvent from the materials after they have been cleaned.

Another object is to produce an efficient, 30 strong and durable degreasing apparatus which may be economically constructed and operated.

Other objects and advantages will herein-after appear.

35 The views of the drawings are:—

Figure 1 is a side elevation, partly in section, of an apparatus constructed according to the preferred embodiment of the invention;

40 Fig. 2 is a view of one end thereof;

Fig. 3 is a fragmentary view of the opposite end, as seen from the line 3—3, Fig. 1; and

Fig. 4 is a detail vertical section as seen 45 from the line 4—4 of Fig. 1.

By my invention, I have provided an apparatus which is primarily adapted to be used in cleaning establishments for the purpose of dry cleaning wearing apparel, although it is to be understood that the appa-

ratus can be used for other similar purposes, such for instance, as for cleaning raw wool, etc. In order to reduce the danger of explosions and fires caused by using volatile liquids for cleaning purposes, I prefer to use 55 an anhydrous neutral liquid as a solvent. The apparatus is provided with a storage tank for the liquid, and means are included in the apparatus for removing all dirt and other foreign matter from the used liquid, and for also removing all the adhering solvent from the materials after they have been cleaned, so that such materials will be dry 60 and odorless when removed from the apparatus.

65 Referring to the drawings, the apparatus comprises a storage tank 5 having an inlet 6 closed by means of a detachable cover 7. The cover should fit tightly on to the tank.

The tank 5 is supported a suitable distance 70 above the floor, and near its bottom the tank is provided with an outlet 8 that is connected to a cleaning machine 9 by a pipe 10.

75 The pipe 10 has mounted therein a ceramic valve 11, which may be of any approved form for controlling the flow of the cleaning liquid from the supply tank 5 to the machine 9.

80 The machine 9 may be of any approved type such as those used by laundries, and other cleaning establishments. The machine, however, should be provided with a tightly fitted door 12 that is removably retained in position by means of a locking device 13, of any desired construction.

85 The machine 9 comprises a cylindrical casting in which is mounted a skeleton drum 14. The drum is adapted to be driven by an electric motor 15, or other source of power, through suitable gearing 16 so constructed as to impart a reverse rotary motion to the drum. This driving means may be of any of the approved forms which are universally used for causing a rotary motion for a limited amount in one direction, and rotary motion for the 90 same number of revolutions in the opposite direction.

95 The drum 14 should preferably be made from wood slats, and it should have an opening in its side which is closed by a removable 100

door 141, to permit access to be had to the interior of the drum.

The pipe 10 should enter the machine 9 at a distance above the bottom thereof, so that a suitable quantity of the cleaning liquid can be delivered into the machine.

Surrounding the lower half of the side of the machine 9 is a semi-cylindrical jacket 17 that forms a closed chamber.

On one side of the machine, near the top of the jacket 17, is an inlet 18, while on the opposite side of the machine, and also near the top of the jacket 17, there is an outlet 19. The bottom of the jacket is provided with a drain cock 20.

A steam pipe 21 is connected to the inlet 18, and a steam pipe 22 is connected to the outlet 19.

The chamber formed by the jacket 17 is adapted to be heated by steam, as will be hereinafter more fully described.

One end of the machine 9 may have a gauge 23 for indicating the amount of liquid therein. There is also a thermometer 24 installed on the end of the machine 9 for indicating the amount of temperature therein. Likewise, the tank 5 is provided with a liquid gauge 25.

Mounted above the tank 5 is another tank 26. The tank 26 is of the same general size and construction as the tank 5.

The machine 9 has an outlet 27 in its bottom, through which the liquid may be withdrawn from the machine. A valve 28 is fixed to the outlet 27 for controlling the flow of the liquid from the machine.

A trap 29, having a removable top 30 is mounted in a pipe line 31 leading from the valve 28 to the tank 26.

In the pipe line 31 there is a pump 32 for forcing the liquid from the trap 29 upwardly into the tank 26. This pump may be driven by any suitable means (not shown), and it may be of any desired type.

The tank 26 serves as a storage tank for the dirty liquid, and it has a gauge 33 for indicating the level of the liquid therein.

The tank 26 can have an opening 34 formed in its top, such opening being closed by a cover 35.

One end of the tank 26, near the bottom thereof, is connected to a distilling apparatus 36, by means of a pipe 37, provided with a ceramic valve 38, similar in form to the valve 11.

The distilling apparatus 36 comprises a cylindrical casing in which is disposed a coiled pipe 39. The pipe enters the casing near the bottom thereof, and leaves the casing near the top thereof.

The pipe 39 is connected to pipes 40 and 41.

Steam from a suitable source of supply is delivered to the pipe 39 through the pipe 40 and returned therefrom through the pipe 41.

A gauge 60 is mounted exteriorly of the

casing of the distilling apparatus 36 for indicating the quantity of liquid therein.

The bottom of the casing of the distilling apparatus 36 is closed by a plate 42.

Beneath the plate 42 there is a bottom cap 43, having a steam pipe 44 connected to its side, and a drain cock 45 in its bottom. This cap provides a closed chamber that is separated from the distilling apparatus 36 by the plate 42.

If so desired, the bottom of the casing of the distilling apparatus 36 may be flanged, and the plate 42 and the cap 43, which latter may have its upper edge flanged, can be attached to the flange of the casing by means of bolts 46. Gaskets 47 being disposed on each side of the plate 42 between the flanges provide a tight connection between the several parts.

The casing of the distilling apparatus 36, above the plate 42, is provided with a flanged opening 48, closed by a removably attached cover 49. The opening 46 is for the purpose of permitting access to the interior of the distilling apparatus 36, so that the accumulation of silt therein may be removed.

The top of the casing of the distilling apparatus 36 is tapered, as indicated at 50.

A pipe 51 is connected to the top of the distilling apparatus 36, and this pipe leads to a coiled pipe 52, disposed in a cylindrical tank 53, constituting a condenser.

The lower end of the pipe 52 passes through the side of the tank 53, near to the bottom thereof, and is connected to the tank 5 by a pipe 54.

Between the tank 5 and the tank 53, the pipe 54 has a ceramic valve 55 mounted therein. This valve is similar in design to the valves 11 and 38 previously described.

The tank 51 has an inlet 56 and an overflow pipe 57. This tank is adapted to be filled with a cooling fluid, such as water, which can be admitted to the tank through the inlet 56 and discharged therefrom through the pipe 57.

The top of the machine 9 has mounted thereon a cylindrical casing 58, the upper end of which is tapered, like the top of the distilling apparatus 36.

The top of the casing 58 has a pipe 59 leading therefrom to the pipe 51, and in this way the interior of the machine 9 is in direct communication with the condenser 53.

In operation, assuming that the machine 9 is empty, the door 12 and the door 141 of the drum 14 are first opened.

A desired quantity of the materials to be cleaned is placed in the drum and its door closed. Then the casing of the machine 9 is hermetically sealed by closing the door 12 and fastening the same by means of the locking device 13.

The valve 11 is now opened to permit a quantity of the cleaning liquid from the tank

5 to flow into the machine, the gauge 23 indicating the amount of liquid in the machine. When the desired level is obtained, the valve 11 is closed and the machine started.

5 After a sufficient run, the machine is stopped and the valve 28 opened. The pump 32 is now set in motion to force the dirty liquid into the tank 26. When all of the dirty liquid has been withdrawn from the 10 machine 9, the pump is stopped and the valve 28 closed.

The valve 11 is now opened to permit a quantity of clean liquid to flow into the machine. The machine is run again for a few 15 minutes so that the clean liquid will rinse the materials in the drum, after which the liquid can be drawn off as previously described and pumped in the tank 26.

This operation can be repeated until all 20 dirt and dirty liquids have been removed.

Steam is now run into the jacket through pipe 21 to heat the bottom of the machine. The steam is circulated through the jacket so as to increase the temperature inside of 25 the machine sufficiently to remove all the solvent in the materials in the drum, the spent steam passing out of the jacket through the pipe 22.

By heating the interior of the machine 9 30 in this manner, the cleaning solvent is vaporized, and the gas passes upwardly through the casing 58, the pipes 59 and 51 and into the coil 52 where it is condensed and flows as liquid through the pipe 54 back into the 35 tank 5.

After all of the solvent has been removed from the materials in the drum 14, the door 12 is opened and the materials removed from the drum. If the materials that have been 40 cleaned by the process are wearing apparel, they will be ready for immediate pressing. Due to the fact that all the solvent will have been removed therefrom, the materials will be odorless.

45 When the tank 26 contains a quantity of dirty liquid and it is desired to replenish the supply in tank 5, the valve 38 is opened and the liquid in tank 26 permitted to flow into the distilling apparatus 36.

50 During operation of the distilling apparatus 36, steam is circulated through the coil 39 which is surrounded by the dirty liquid.

The heat from the coil 39 will heat the liquid in the distilling apparatus 36 sufficiently to turn the same into vapor. The vapor will pass upwardly through the top of the still and then through the pipe 51 into the coil 52 of the condenser. The vapor will be then condensed, and will then flow through 60 the pipe 54 back into tank 5.

In transforming the liquid in the distilling apparatus 36 into vapor, the heavy particles of dirt and silt will be deposited in the bottom of the casing of the distilling apparatus, 65 resting on the plate 42 (see Fig. 4).

The silt deposited in the bottom of the distilling apparatus may be removed, from time to time, through the opening 48. However, in order to conserve all of the solvent, before removing the silt from the bottom of the distilling apparatus, steam can be admitted through the pipe 44 into the chamber provided by the cap 43. In this way the silt can be heated and all the solvent therein turned to vapor to pass upwardly through the 70 casing of the distilling apparatus 36, in much the same general manner as the solvent is removed from within the machine 9.

75 It will be understood that all of the solvent will be conserved because all of the units of the device are connected in such a way as to prevent entrance of air thereto, and as the solvent used is non-flammable, fires or explosions will be prevented.

80 The invention set forth herein is, of course, susceptible of various modifications and adaptations.

The invention claimed is:—

1. A degreasing apparatus including a supply tank for the cleaning liquid, means for 90 cleaning the materials, said means being connected to the said supply tank, a tank for the dirty cleaning liquid, means for pumping the liquid from the cleaning means to the said dirty liquid tank, heating means for the 95 cleaning means for vaporizing the remaining solvent in the materials after the major portion of the solvent has been withdrawn, for removing saturation, and means comprising a tank of large diameter directly connected to said cleaning means for quickly 100 withdrawing the vaporized solvent.

2. A degreasing apparatus including a supply tank for the cleaning liquid, means for 105 cleaning the materials, said means being connected to the said supply tank, a tank for the dirty cleaning liquid, means for pumping the liquid from the cleaning means to the said dirty liquid tank, a condenser connected to said supply tank, means for distilling the liquid from said dirty liquid tank and for passing the same through the said condenser, heating means for the cleaning means for vaporizing the remaining solvent in the materials after the major portion of the solvent 110 has been withdrawn to the dirty liquid tank, and means comprising a tank of large diameter directly connected at one end of said cleaning means, and at its other end to said condenser, for quickly withdrawing the vaporized solvent.

3. A degreasing apparatus comprising means for cleaning the materials with a liquid, means for drawing off the cleaning liquid from the cleaning means, means for vaporizing the liquid remaining in the cleaning means, means for condensing the vapor, and large-size means directly connecting said cleaning means with said condenser, permit-

ting quick removal of excess vapors in said cleaning means.

4. In degreasing apparatus, a closed unvented series comprising a cleaning tank, a pump for discharging the contents of the cleaning tank, a dirty liquid tank to which the pump discharges, a still to which the dirty liquid tank discharges, a condenser to which the still discharges and a clean liquid tank to which the condenser discharges, said clean liquid tank having a controllable discharge connection to said cleaning tank and a connection between the cleaning tank and the condenser permitting the circulation of vaporized cleaning liquids therebetween, said connection comprising a tank of relatively large diameter.
